WALKING-BEAM AND COUNTERBALANCE
CONSTRUCTION

Walter E. Saxe, Alhambra, Calif.

Application April 4, 1938, Serial No. 199,906

14 Claims. (Cl. 74—589)

My invention relates in general to mechanisms that include lever means for producing straight-line reciprocation, more particularly mechanism for such purpose in which the major load is primarily in only one direction of the reciprocation. For the purpose of illustrating the principles involved in my invention, the present disclosure is directed specifically to a mechanism for pumping oil wells, but it is to be understood, as will be apparent to those skilled in the art, that the principles of my invention may be embodied in various mechanisms for various purposes where straight-line reciprocation is requisite.

15 An oil well pumping mechanism of the type involved here is built around a walking-beam, the walking-beam being oscillated by power means and being connected at its working end to a string of rods extending down into the oil well. 20 Since the working end of the walking-beam moves in an arcuate path, it is desirable to provide the walking-beam with arcuate means commonly termed a "mule-head" in tangential engagement with flexible means interconnecting the working end of the walking-beam and the string of rods in the well. In the conventional arrangement, the mule-head required is necessarily of considerable vertical extent, with the result usually that considerable head room is required at the top of the stroke and on the down-stroke the mule-head is a hazard to workmen.

25 An important object of my invention is to reduce the arc or vertical length of the mule-head required for a given pump stroke. In this regard my invention is based on the concept that the arcuate extent of the mule-head may be materially reduced if the walking-beam has one pivot, concentric with the curvature of the mule-head, that reciprocates in a straight line parallel with the straight-line motion of the pump rods, all the other pivotal connections of the walking-beam shifting as required to accommodate this parallel movement. Since guide means is required to restrict movement of the selected 30 pivot to a straight line, this pivot will be referred to as the "guide pivot". The walking-beam, operating on my principle requires a second pivot anchored or restricted in a manner to permit shifting thereof, as required, to accommodate the straight-line motion of the guide pivot. This second pivot will be termed, for convenience, the "fulcrum pivot", but it is recognized that the action of the walking-beam may be analyzed with the guide pivot taken as the 35 fulcrum.

A feature of my invention is that the center of curvature of the mule-head is shortened to the guide pivot instead of extending to the fulcrum pivot. This fact is important, because this radius controls the length of the mule-head. 5

In pumping oil or in reciprocating a string of drill tools, the load on a walking-beam is primarily in one direction of reciprocation. A feature of my invention is the application of counterbalancing forces to the guide pivot of such a 10 walking-beam and one of my objects is to combine in one structure means to counterbalance the walking-beam load and means to guide the guide pivot.

In such an installation, in addition to counterbalancing the load on the walking-beam, it is often desirable to provide auxiliary counterbalancing means to equalize the engine load by storing energy when the crank driving the walking-beam passes through each of its two dead-center 20 positions. A further object of my invention, in the forms herein disclosed, is to provide a unitary fluid-pressure system to serve both the purpose of counterbalancing the load on the walking-beam and the auxiliary purpose of equalizing 25 the load on the engine.

Other objects and features of my invention will be apparent in the description to follow, taken with the accompanying drawings.

In the drawings: 30
Fig. 1 is a side elevation partly sectioned of a pumping unit incorporating my invention;

Fig. 1a is a fragmentary view similar to Fig. 1 showing how certain elements in Fig. 1 may be altered to form a modification of my invention; 35

Fig. 2 is a horizontal section taken along the broken line 2—2 of Fig. 1;

Fig. 3 is an end view of the unit partly sectioned;

Fig. 4 is a fragmentary view in side elevation 40 showing a fulcrum pivot construction that may be employed in a modification of my invention;

Fig. 5 is a diagrammatic view to indicate the construction of a second form of my invention;

Fig. 6 is a diagrammatic view showing how 45 the configuration of the mule-head of Fig. 1 may be altered for the purpose of reciprocating pump rods in a non-vertical direction.

Fig. 7 is a fragmentary view of a walking-beam construction that may be employed in an- 50 other form of my invention;

Fig. 8 is a section through a bearing of Fig. 7 taken as indicated by the line 8—8 of Fig. 7; and

Fig. 9 is a diagrammatic view to illustrate the

principle of operation in the walking-beam of Fig. 7.

Fig. 1 shows a typical installation of the preferred form of my invention for operating a deep well pump conventionally shown at 10 through the medium of a string of sucker rods 11, the pump being in a string of tubing 12 in the well casing 13. At the top of the well is a casing head 14 having the usual lateral pipes 15 and also the usual vertical pipe 16 having a lateral branch 17 through which oil is delivered from the well. The uppermost sucker rod, the polish rod 18, passes through a packing gland 19 in the pipe 16.

The mechanism for actuating the well pump is mounted on a box-like frame 20 on foundation blocks 22, the frame supporting on its upper side a platform 23. A walking-beam 24 is pivotally mounted on and guided by vertically movable means generally designated by the numeral 25. In the particular construction shown in the drawings, the walking-beam comprises a pair of side plates 26 having trunnions 27 to provide a fulcrum pivot at one end of the beam, trunnions 28 at an intermediate point to provide a drive pivot for actuating the beam, and guide bearings 29 to receive trunnions 30 of the vertical guide means 25, the trunnions 30 providing the guide pivot for the walking-beam. The guide pivot divides the beam into a forward arm 32 having its working end extending to the axis of the well casing, and a rearward arm 33 having the fulcrum pivot 27.

The forward arm 32 is operatively connected with the sucker rods 11 of the well by suitable means such as a flexible member 34. The flexible member may be a rope or cable looped over a saddle 35 at the forward end of the walking-beam, the two ends of the flexible member being anchored to a suitable cross bar 36 at the upper end of the polish rod 18. The forward or working end of the walking-beam is provided with the usual arcuate means or mule-head 37 providing two channels for tangential engagement with the flexible member 34, the mule-head being concentric with the trunnions 30 of the vertical guide means.

This first form of my invention is based on the concept of restricting the vertical movement of the fulcrum pivot while permitting such pivot freedom for movement in a generally horizontal direction. My object here is to permit the arc of the mule-head to be shortened by causing the fulcrum pivot to shift toward the axis of the pump rods at both the upper and lower ends of the pump stroke. In accordance with this conception, at the rear end of the walking-beam the trunnions 27 are journaled in the upper ends of a pair of fulcrum links 38, the lower ends of which are keyed to a rocker shaft 39 journaled in a pair of bearings 40 on the platform 23. The fulcrum links limit the vertical movement of the fulcrum pivot of the walking-beam but constitute a flexible anchoring means since they permit lateral shifting of the fulcrum pivot.

The walking-beam is actuated by a pair of drive cranks 42 through a corresponding pair of connecting rods 43 engaging the trunnions 28. The vertical guide means 25 restricts the movement of the guide pivot of the walking-beam, i. e., the trunnions 30, the fulcrum pivot of the walking-beam shifting as required to permit such vertical movement. It is apparent that the walking-beam has no fixed pivot and that the curvature of the path traversed by the drive pivot is much

less in this arrangement than in the conventional arrangement for oscillating a walking-beam about a fixed pivot.

While any type of vertical guide means may be provided for the guide pivot of the walking-beam, as will be readily understood by those skilled in the art, I prefer in the present embodiment of my invention to incorporate the vertical guide means in the construction of a fluid-pressure counterbalance for the walking-beam, as 10 will now be described.

The counterbalancing means includes a vertical hydraulic cylinder 44 and one or more, preferably two, associated upright tanks 45 and 46 together with a horizontal air receiver 47, the air receiver being within the frame 20 under the platform 23. The hydraulic cylinder 44 is open to the atmosphere at the top and opens at the bottom into a U-shaped chamber 48 that interconnects the two tanks 45 and 46. Mounted in 20 the hydraulic cylinder 44 is a piston 49 extending upward from which is a piston rod 50. The piston rod is guided not only by the piston itself, but also by an upper guide means at the top end of the hydraulic cylinder comprising a spider 52 having a guide collar 53, and an intermediate guide means comprising a collar 54 at a lower level. Supported by the upper end of the piston rod 50 is an outer cylinder 55 that is telescoped over the hydraulic cylinder in spaced relation 30 thereto. The aforementioned guide bearings 29, associated with the guide pivot of the walking-beam, are carried by this cylinder so that the hydraulic cylinder, the piston, the piston rod, and the two guide means for the piston rod 35 cooperate to restrict movement of the guide pivot of the walking-beam to a vertical path substantially parallel with the axis of the sucker rods in the well.

At least one of the two vertical upright tanks 40 45 and 46 is provided at the top with a relief pipe 56 having a relief valve 57, and both of the tanks are connected by a pipe 58 and a pipe 59 with the air receiver 47, the pipe 59 preferably being provided with a suitable cutoff valve 60. A suitable quantity of liquid, such as oil, within the U-shaped chamber 48 below the piston 49, surges up and down in the upright tanks 45 and 46 in accordance with the reciprocations of the piston, the liquid at its uppermost level in the tanks 50 45 and 46 being substantially below the pipe 58, the movement of the liquid upward being in opposition to the pressure of the air in the receiver 47.

Incorporated in the piston 49 may be a pump 55 arrangement for returning to the liquid body any leakage upward past the piston. The drawings show a return pipe 62 extending above the piston and communicating with an inlet passage 63 leading to a vertical pump bore 64. A pump plunger 60 65 mounted to reciprocate in the bore 64 is normally held at an upper position by a spring 66. As the piston 49 approaches the upper limit of its range of movement, the return pipe 62 and the plunger 65 enter corresponding bores in the 65 collar 54 and the plunger then impinges on a stop member 68 that causes the plunger to move downward in the vertical bore 64 to force any liquid therein outward through a check valve 69 into the fluid body below the piston. Since the 70 return pipe 62 extends a substantial distance above the upper face of the piston, a substantial quantity of liquid will be retained in a pool on the upper side of the piston. This oil lubricates substantially the entire length of the piston rod 75

by virtue of the fact that the upward movement of the piston causes the collar 54 to be bathed in oil and the downward movement of the piston brings the upper portion of the piston rod 50 into contact with the collar 54, the collar being tapered as shown, to retain oil around the periphery of the piston rod.

Any suitable power plant may be provided for actuating the walking-beam 24. In the preferred form of my invention an engine 70 drives a train of gears carried by a frame 72 in a gear housing 73, the driving means including an engine pulley 74, a belt 75, and a large pulley 76 mounted on the exterior of the housing 73 on a shaft 77. A pair 5 of spaced spur gears 78 keyed to the shaft 77 engages corresponding large gears 79 on a shaft 80. An intermediate spur gear 81 keyed to the shaft 80 meshes with a counterbalance gear 82 on a shaft 83. The counterbalance gear 82 in 10 turn meshes with a larger gear 84 on a shaft 85 that carries the two drive cranks 42.

Keyed to the opposite ends of the shaft 83 that carries the counterbalance gear 82 is a pair 5 of counterbalance cranks 86 that rotate twice as fast as the drive cranks 42 and are connected with suitable auxiliary counterbalancing means to equalize the load on the engine 70. In the preferred form of my invention this auxiliary counterbalancing means operates against the 10 pressure of the fluid-pressure arrangement already described.

In the arrangement suggested by the drawings, an auxiliary cylinder 87 mounted on the top of the gear housing 73 is connected toward its lower 5 end with a pipe 88 that enters the side of the upright tank 46 and extends downward therein to terminate in the counterbalancing liquid well below the lowermost level of that liquid. A piston 89 mounted in the auxiliary cylinder 87 is connected with a piston rod 90 that extends upward through a suitable guide spider 92 at the top of the cylinder. Preferably the upper end of the auxiliary cylinder will be protected by an inverted cylinder 93 carried by the piston rod. 15 Also carried by the piston rod is a bracket 94 in which is mounted a laterally extending shaft 95, which shaft is operatively connected with the counterbalancing cranks 86 by a pair of connecting rods 96. The angular relation of the 20 counterbalancing cranks 86 to the drive cranks 42 is such that the counterbalance piston is moved against counterbalance pressure as the drive cranks 42 swing past their upper and lower dead centers. The downward movement of the 25 auxiliary counterbalancing piston 89 forces oil into the main counterbalancing system in opposition to the pressure from the air receiver 47. If desired, the piston 89 may be provided with means such as incorporated in the main piston 30 49 to return oil leaking upward past the piston.

Automatic means to maintain the pressure in the air receiver 47 may be provided in a manner now to be described. A suitable air pump 98 alongside the auxiliary cylinder 87 has an operating piston rod 99 connected to a bracket 100 extending laterally from the aforementioned bracket 94 at the top of the piston rod 90 so that the air pump is operated by the reciprocations of the auxiliary counterbalancing means. Air 45 from the pump 98 is delivered into a small high-pressure receiver 102 through a delivery pipe 103 equipped with a check valve 104 and a pressure gauge 105. The air receiver has the usual safety valve 106 and is connected with the horizontal 50 air receiver 47 through a pipe 107. The pipe 107

has a reduction valve 108 below which is a second pressure gauge 109.

Preferably the displacement of the air pump 98 will be such as to maintain the pressure in the tank 102 at a value substantially above any counterbalance pressure required in service. This pressure may be varied at will by varying the point at which the piston rod 99 is connected to the bracket 100. Whenever the pressure in the tank 102 reaches the limit determined by the displacement of the pump 98, the delivery of air into the tank 102 will cease automatically but will be resumed whenever the pressure in the tank drops below that point. The pressure regulator 108 is adjusted to step down that pressure to the 15 particular counterbalancing pressure required by the load on the walking-beam.

The operation of my pumping unit may readily be understood from the foregoing description. It will be noted that by virtue of the fact that 20 the guide pivot of the walking-beam is moved in an absolutely straight line, the mule-head 37 concentric with the guide pivot transmits forces to the well pump along the axis of the string of 25 pump rods at all angles of the walking-beam.

It will be noted that in Fig. 1 the fulcrum pivot 27 shifts laterally in a slightly arcuate path. Instead of the fulcrum links 38, a cross-head 112 (Fig. 4) operating between a pair of horizontal guides 113 may be provided to limit the fulcrum pivot of the walking-beam to strictly horizontal movement, the walking-beam extending to opposite sides of the cross-head and being connected to a pivot pin 114 extending through the cross-head. It is apparent that the arrangement to 30 which Figs. 1 to 4 refer transmits force in the desired direction with a much shorter mule-head than would be necessary were the walking-beam oscillated about a fixed pivot in the conventional manner.

In the second form of my invention the fulcrum pivot at the opposite end of the walking-beam from the working end is provided with arcuate means in rolling engagement with a fixed member, the walking-beam being provided, for 45 example, with a second mule-head at the fulcrum pivot in tangential engagement with an anchored flexible member, whereby the effective fulcrum point simultaneously reciprocates vertically and travels around the curve of the second mule-head; 50 the vertical movement of the guide pivot being thus accommodated by rolling action at the fulcrum end of the walking-beam. This second form of my invention is based on the concept of dividing the function of a mule-head between two 55 mule-heads on opposite ends of the walking-beam, whereby the arcuate extent of either mule-head may be reduced to one-half or less the arcuate extent of a single mule-head. My invention in this second form may be regarded in still 60 another aspect, namely, as the concept of applying to a walking-beam construction the principle of a giant sheave on a vertically shifting axis with an anchored flexible member extending over the sheave to the pump rods.

In Fig. 5, indicating the manner in which this second form is constructed, a vertical guide means 122 determines the path of a guide pivot 123 for the walking-beam 124, the guide pivot dividing the walking-beam into a forward arm 125 and a rearward arm 126. The forward arm of the walking-beam has a mule-head 37a connected to a flexible member 34a, as previously described. The rearward arm 126 of the walking-beam has a similar mule-head 127 in similar 75

- 5 tangential engagement with a second flexible member 128, but this second flexible member is anchored at a fixed point 129. This arrangement of a mule-head and anchored flexible means may be regarded as providing a fulcrum pivot for the walking-beam, which fulcrum pivot shifts vertically to a limited extent when the walking-beam is oscillated by force transmitted through the connecting rods 130.
- 10 In the preferred form of my invention, the secondary cylinder 87 is connected through the pipe 88 to the main fluid-pressure counterbalancing system. A feature of my invention is the conception of completely separating the auxiliary cylinder 87 from the main fluid-pressure system and utilizing the reciprocation of the piston 89 in that cylinder not only for the purpose of counterbalancing the crank 86, but also for the purpose of pumping air to the main fluid-pressure system. Such a modification is suggested by Fig. 1a in which the piston 89a that reciprocates in the auxiliary cylinder 87a is provided with an air intake valve 131. The pipe 88 of Fig. 1 as well as the air pump 98 are omitted. The pipe 103a 20 leading to the high-pressure receiver 102a is connected to the bottom of the cylinder 87a. This pipe is equipped with a check-valve 104a, a pressure gauge 105a, and a pressure regulator 132, the pressure regulator being between the check-valve and gauge.
- 25

As the piston 89a descends, it compresses air in the cylinder 87a. Whether air so compressed passes to the high-pressure cylinder tank 102a depends upon the setting of the pressure regulator 132 and the relation of that setting to the pressure in the high-pressure tank. It is apparent that various adjustments may be made to vary the pumping action in the reciprocation of the piston 89a and the amount of energy delivered back to the crank 86 when the piston 89a moves upward. In one mode of operation the auxiliary counterbalance arrangement of Fig. 1a would automatically deliver air into the high-pressure tank 102a whenever the pressure in that tank falls below a predetermined value. In another mode of operation the pressure regulator 132 would serve, in effect, as a cutoff valve that will be normally closed to permit the air in the cylinder 87a to reach relatively high pressures for counterbalancing purposes; whenever required, as indicated by the gauge 105a, the operator would adjust the pressure regulator 132 for a temporary period of pumping operation.

While usually my invention will be employed for reciprocating a truly vertical polish rod, the path of the guide pivot of the walking-beam being parallel to the axis of said polish rod, in some installations where the top of the well is out of line, my invention will be employed for non-vertical reciprocation and the path of the walking-beam guide pivot will be non-parallel to the axis of the polish rod. My invention may be readily adapted to such a situation by making the curvature of the mule-head such that the mule-head will be throughout its range of movement substantially tangential to the axis of the polish rod. Illustrating such an arrangement, Fig. 6 shows a walking-beam 135 pivotally connected at one end to a pair of fulcrum links 136 and connected at the other end by a flexible member 137 to a polish rod 138. It will be noted that this polish rod and the flexible member 137 coaxial therewith are out of vertical alignment, whereas, the vertical guide means 139 is disposed to move the guide pivot 140 of the walking-beam

in a substantially vertical path. The profile configuration of the mule-head 141 at the working end of a walking-beam is, therefore, an irregular curve that at all points in the reciprocation of the walking-beam is substantially tangential to the axis of the polish rod 138.

In another form of my invention I may substitute a linkage arrangement for the mule-head at the working end of the walking-beam, as suggested by Figs. 7 to 9. The drawings show a walking-beam 143 pivoted to a pair of fulcrum links 144 and driven by a pair of connecting rods 145 previously described. The vertical guide means 146 has trunnions 147 journaled in bearings 148 of the walking-beam to provide the usual guide pivot.

Mounted on a shaft 149 at the outer end of the walking-beam is a rocker member generally designated 150 that includes two arms 151 mounted on the shaft 149 and interconnected at their upper ends by a rod 152. The upper end of the rocker member 150 is tied to the vertical guide means 146 by a link 153 that rotatably engages the rod 152 and a pin 154 that is carried by a bracket 155 on the vertical guide means. The lower end of the rocker member 150 is connected to the polish rod 156 by a suitable bearing means generally designated 157.

The bearing means 157, preferably, as shown in the drawings, incorporates a bearing construction described in my copending application Serial No. 156,980, filed August 2, 1937, entitled Method of and apparatus for lubricating walking beam bearings. The drawings show two bearing housings 158, one at the lower end of each of the arms 151 of the rocker member, each of the housings being made in two parts connected by a suitable bolt means 159. Within each of these housings is a rotary bearing member 160 having a plurality of eccentric sections that rest on a complementary journal seat 161, the two rotary bearing members being interconnected by a common rocker shaft 162. The polish rod 156 may be connected to the shaft 162 in any suitable manner. In the drawings it extends diametrically through the shaft 162 and terminates in nuts 163 that rest against a suitable washer or collar 164.

Fig. 9 indicates how the rocker member 150 and the link 153 may be so related to the walking-beam and to the vertical guide means as to result in straight-line movement of the bearing 157. At the uppermost position of the working end of the beam the bearing is at the position 149a, the positions of the link 153 and the rocker arm being indicated by dotted lines; when the walking-beam is approximately horizontal the bearing is at 149b, the link and rocker member being at positions indicated by dot-dash lines; at the lowermost position of the working end of the walking-beam, the link and rocker arm are in the dash-line positions, placing the bearing member at 149c. For a ten foot pump stroke the vertical guide means 146 may, for example, be reciprocated seven feet and the walking-beam oscillated to move the bearing 157 an additional three feet in the straight line indicated.

I have shown and described preferred embodiments of my invention in specific detail for the purposes of disclosure and to illustrate the principles involved. It will be apparent to those skilled in the art that various changes and modifications may be made without departing from the spirit of my invention. I reserve the right to all such changes and modifications that prop-

erly come within the scope of my appended claims.

I claim as my invention:

1. In a device of the character described for reciprocating a member in a well, the combination of: a walking-beam operatively connected with said member; means pivotally connected with the walking-beam to raise and lower the walking-beam; means flexibly anchoring a fulcrum point of the walking-beam to cause the beam to oscillate when so raised and lowered; guide means restricting one point of the walking-beam to substantially straight line motion; and a counterbalance means operatively connected with the walking-beam at said guided point. 5
2. In a device of the character described for reciprocating a load member in substantially a straight line, the combination of: a walking-beam; means pivotally connected with the walking-beam to raise and lower the walking-beam; means flexibly anchoring a fulcrum point of the walking-beam to cause the beam to oscillate when so raised and lowered; guide means restricting one point of the walking-beam to substantially straight line motion; means at the working end of the walking-beam to compensate for movement thereof with respect to said straight line; and means interconnecting said load member and said compensating means. 10
3. Means of the character described for transmitting force in substantially a straight line to a load member, said means comprising: guide means adapted to reciprocate in a substantially straight line; a rocker member pivoted at an intermediate point to said guide means, said rocker member having a fulcrum end and a working end; means extending along said first-mentioned straight line for interconnecting said load member and the working end of said rocker; means 15 at said working end of the rocker member in engagement with said interconnecting means to compensate for the arcuate path of said working end; anchor means connected with the fulcrum end of the rocker member to permit shifting thereof as required by said guide means; and power means to oscillate said rocker member. 20
4. Means of the character described for transmitting force in a substantially straight line to a driven member to move the driven member periodically in opposition to a load, said means comprising: guide means adapted to reciprocate in a path substantially parallel with said straight line; a rocker member pivoted at an intermediate point to said guide means, said rocker member having a fulcrum end and a working end, the latter end extending to said straight line; means extending along said straight line interconnecting said load member and the working end of said rocker; arcuate means at said working end of the rocker member in tangential engagement with said interconnecting means, said arcuate means being substantially concentric to the pivotal connection of the rocker member with said guide means; flexible anchoring means connected to the fulcrum end of the rocker member; power means to rock said rocker means in the direction opposed to said load; and counterbalancing means connected with said rocker means to oppose the opposite movement of the rocker member. 25
5. Means of the character described for transmitting force in substantially a straight line to a driven member to move the driven member periodically in opposition to a load, said means comprising: guide means adapted to reciprocate in a path substantially parallel with said straight line; a rocker member pivoted at an intermediate point to said guide means, said rocker member having a fulcrum end and a working end, the latter end extending to said straight line; means extending along said straight line interconnecting said load member and the working end of said rocker; arcuate means at said working end of the rocker member in tangential engagement with said interconnecting means, said arcuate means being substantially concentric to the pivotal connection of the rocker member with said guide means; anchor means connected with the fulcrum end of the rocker member to permit shifting thereof as required by said guide means; and power means to rock said rocker means in the direction opposed to said load; and counterbalancing means acting upon said guided point of the rocker member to oppose the opposite movement of the rocker member. 30
6. Means for actuating pump rods or the like in a well, said means including: a beam having a guide pivot and a fulcrum pivot; guide means providing a substantially straight path for said guide pivot; anchor means for said fulcrum pivot adapted to permit lateral shifting thereof as required for vertical movement of the guide pivot; arcuate means on said beam concentric to said guide pivot and substantially tangential to said pump rods; means engaged by said arcuate means to operatively connect said beam with the pump rods; and power means to move the beam upward against the load on said pump rods. 35
7. Means for actuating pump rods or the like in a well, said means including: a beam having a guide pivot dividing the beam into forward and rearward arms; guide means to limit movement of said guide pivot to a substantially vertical path; flexible means substantially in alignment with the axis of said pump rods interconnecting the pump rods and the forward arm of the beam; means on the forward arm of the beam engaged with said interconnecting means and adapted to compensate for the arcuate character of the arm movement; a second flexible means having its lower end anchored and its upper end connected to the rearward arm of the beam; arcuate means on said rearward arm of the beam concentric with said guide pivot in tangential engagement with said flexible means; and means to actuate said beam. 40
8. Means for actuating pump rods or the like in a well, said means including: a beam having a guide pivot dividing the beam into forward and rearward arms; guide means to limit movement of said guide pivot to a substantially vertical path; flexible means substantially in alignment with the axis of said pump rods interconnecting the pump rods and the forward arm of the beam; arcuate means on the forward arm of the beam concentric with said guide pivot in tangential engagement with said flexible means; a second flexible means having its lower end anchored and its upper end connected to the rearward arm of the beam; arcuate means on said rearward arm of the beam concentric with said guide pivot in tangential engagement with said second flexible means; and means to actuate said beam. 45
9. Means for actuating pump rods or the like in a well, said means including: a vertically movable fluid-pressure-actuated counterbalancing means exerting force in an upward direction; a rocker member pivotally mounted on said counterbalancing means; means substantially coaxial 50

- with said pump rods interconnecting the pump rods and the beam; means on the rocker member in engagement with said interconnecting means to compensate for curvature in the movement of the rocker member; fulcrum means connected with said beam in a flexible manner to permit vertical movement of the pivotal point of the beam; a drive crank operatively connected with the beam to lift the beam in opposition to the load on said pump rods; power means to actuate said drive crank; a counterbalancing crank operatively connected with said drive crank to make two revolutions for one revolution of the drive crank; and fluid-pressure-actuated counterbalancing means operatively connected to said counterbalancing crank to equalize the load on said power means.
10. Means of the character described for actuating a load member in a well, said means including: a walking-beam operatively connected with said load member; a drive crank operatively connected with the beam; power means to actuate the drive crank; a fluid-pressure counterbalancing means adapted to oppose the downward movement of the beam to equalize the load on said drive crank; a counterbalance crank operatively connected with said drive crank to make two revolutions for every revolution of the drive crank; and fluid-pressure counterbalancing means adapted to oppose movement of said counterbalancing crank in one direction to equalize the load on said power means.
11. Means of the character described for actuating a substantially vertical movable member in a well, said means including: a beam having a pivot dividing the beam into a forward arm and a rearward arm; means to guide said pivot along a substantially vertical path; means substantially coaxial with the well interconnecting said means in the well with the forward arm of said beam; means on the beam in engagement with said interconnecting means to compensate for curvature in the path of said end of the rocker member; means anchoring the rearward arm of the beam in a flexible manner to permit the vertical movement of said pivot point of the beam; a drive crank operatively connected with the beam to move the beam in opposition to the downward force transmitted by said interconnecting means; power means to actuate the drive crank; a counterbalance crank operatively connected with said drive crank to make two revolutions for every revolution of the drive crank; and fluid-pressure counterbalancing means adapted to oppose the downward movement of the beam to equalize the load on said said power means.
12. Means of the character described for actuating a load member in a well, said means including: a walking-beam operatively connected with said load member; a drive crank operatively connected with the beam; power means to actuate the drive crank; a primary fluid-pressure counterbalancing means adapted to oppose the downward movement of the beam to equalize the load on said drive crank; a counterbalance crank operatively connected with said drive crank to make two revolutions for every revolution of the drive crank; and auxiliary fluid-pressure counterbalancing means adapted to oppose movement of said counterbalancing crank in one direction to equalize the load on said power means, said auxiliary counterbalancing means being constructed to serve as a pump for maintaining pressure in said primary counterbalancing means.
13. In a device of the character described for reciprocating a load member in substantially a straight line, the combination of: a walking-beam support adapted to reciprocate in substantially a straight line; a walking-beam pivotally mounted on said support; a rocker member mounted on said walking-beam; means interconnecting one end of said rocker member with said load; and a link interconnecting the other end of the rocker member and said walking-beam support, said link and rocker member being so dimensioned and disposed as to cause the end of the rocker member connected with said load to move in substantially a straight line.
14. In a device of the character described for reciprocating a load member in substantially a straight line, the combination of: a walking-beam having its working end connected to said member substantially in said straight line; power means to raise and lower said walking-beam; means flexibly anchoring a fulcrum point of the walking-beam to cause the beam to oscillate when so raised and lowered; means connected to the walking-beam including a cylinder and a cooperating member slidingly telescoped therein to serve both as a guide to restrict a point of the walking-beam to rectilinear movement and as a counterbalance for the load imposed on the walking-beam; and means at the working end of the walking-beam to compensate for arcuate departure thereof from said straight line.
